UNITED STATES PATENT OFFICE.

WALTER TURTON, OF ARLINGTON, NEW JERSEY, ASSIGNOR TO THE EASTWOOD-PARK COMPANY, OF NEWARK, NEW JERSEY, A CORPORATION OF NEW JERSEY.

DESIGN FOR A BACK FOR MIRRORS, BRUSHES, OR SIMILAR ARTICLES.

SPECIFICATION forming part of Design No. 37,148, dated September 20, 1904.

Application filed August 11, 1904. Serial No. 220,428. Term of patent 7 years.

To all whom it may concern:

Be it known that I, WALTER TURTON, a subject of the King of Great Britain, and a resident of Arlington, in the county of Hudson 5 and State of New Jersey, have invented a certain new, original, and ornamental Design for a Back for Mirrors, Brushes, or Similar Articles, which is illustrated in the accompanying drawing, forming part of this specification, 10 and being a view of the back of an article

having an integral body and handle, as a mirror or brush, showing my new design, which is executed in relief.

What I claim is—

The ornamental design for the back of a 15 mirror, brush or similar article, as shown.

WALTER TURTON.
